(57) **CLAIM**

The ornamental design for a pessary seal, as shown and
described.

DESCRIPTION

FIG. 1 is a perspective view of a first embodiment of a
pessary seal showing our new design;

FIG. 2 is a top view of the pessary seal as shown in FIG. 1;
FIG. 3 is bottom view of the pessary seal as shown in FIG.
1;

FIG. 4 is a back side view of the pessary seal as shown in
FIG. 1;

FIG. 5 is a front side view of the pessary seal as shown in
FIG. 1;

FIG. 6 is a left side view of the pessary seal as shown in FIG.
1;

FIG. 7 is a right side view of the pessary seal as shown in
FIG. 1;

FIG. 8 is a perspective view of a second embodiment of a
pessary seal;

FIG. 9 is a top view of the pessary seal as shown in FIG. 8;
FIG. 10 is bottom view of the pessary seal as shown in FIG.
8;

FIG. 11 is a back side view of the pessary seal as shown in
FIG. 8;

FIG. 12 is a front side view of the pessary seal as shown in
FIG. 8;

FIG. 13 is a left side view of the pessary seal as shown in
FIG. 8;

FIG. 14 is a right side view of the pessary seal as shown in
FIG. 8;

FIG. 15 is a perspective view of a third embodiment of a
pessary seal;

FIG. 16 is a top view of the pessary seal as shown in FIG.
15;

FIG. 17 is bottom view of the pessary seal as shown in FIG.
15;

FIG. 18 is a back side view of the pessary seal as shown in
FIG. 15;

FIG. 19 is a front side view of the pessary seal as shown in
FIG. 15;

FIG. 20 is a left side view of the pessary seal as shown in
FIG. 15; and,

FIG. 21 is a right side view of the pessary seal as shown in
FIG. 15.

The broken line showing of portions of the pessary seal in
included for the purpose of illustrating environmental struc-
ture and forms no part of the claimed design.
